WALKING DOLL PUSH TOY

Violet Gradwohl, Apple Valley, Calif.

Application March 12, 1954; Serial No. 415,795.

2 Claims. (Cl. 46—110)

My invention relates to push and pull toys which comprise a frame supported by wheels and a doll carried by this frame.

Objects of my invention are to simulate a walking body by moving the feet of the doll alternately to and fro relatively to the frame, to cause this movement of the feet by oscillating abutments which engage the feet in the moving direction without substantially impairing the free appearance of the feet, to derive the oscillations of these abutments from the rolling movement of the wheels whereby the doll seems to walk whenever the toy is pulled or pushed ahead, to arrange the means transmitting movement from the wheels to the abutments in a substantially concealed position under a platform of the frame, and thereby to simulate a walking body in a novel, easily operable and amusing manner.

Other objects are to drive the abutments and, hence, the feet in a horizontal direction parallel to the platform of the frame, thereby to provide a naturally appearing walk, to provide sleds guided by the frame for the support of the moving abutments, to move these sleds to and fro by a crank shaft affixed to the wheels and engaging the sleds eccentrically, and thereby to provide simple and reliable means for an accurate movement of the abutments.

Further objects are to provide a frame which can be used with different dolls, to attach a doll to this frame exchangeably, to provide the frame with a pole and with a belt attached thereto at a level which corresponds to the level of the waist of the doll whereby said belt can be used for attaching the doll to the frame in a manner in which the attaching belt appears as a natural accessory of the doll's clothing, and to support the doll body by the pole so that the feet depend into the space between the abutments and can be moved by the latter in a natural manner.

Still other objects are to drive the toy in the forward walking direction of the doll optionally by push or by pull, to provide a handle for this purpose which can be optionally affixed at the rear or at the front of the frame, to adjust the length of the handle according to the size of the child operating the toy, to provide a leg which enables the toy to stand upright, and to connect this leg with the handle whereby the leg changes its position relatively to the frame when the handle is transferred from one side to the other so that the leg will always be at the heavy handle side of the toy.

Still other objects and advantages will appear from the following description of an exemplifying embodiment of my invention, from the appended claims and from the accompanying drawing in which:

Fig. 1 shows a partly sectional side view of an illustrative embodiment of my invention, the sectionally represented parts being cut along the broken line 1—1 in Fig. 3.

Fig. 2 shows a front view of the same embodiment.

Fig. 3 shows a bottom view of the same embodiment.

Fig. 4 shows a top view of the same embodiment.

2

Fig. 5 shows a side view of the same embodiment represented on a smaller scale than Figs. 1 to 4.

In Figs. 1 to 4, the doll is omitted and a portion of the handle is broken off.

Referring to the drawing, numeral 2 indicates a substantially horizontal platform from which two side walls 3 extend downward. Co-axial axles 4 pass through bores or bearings in the walls 3 and are affixed to wheels 5. A crank shaft 6 connects the facing ends of the axles 4 and 10 has two eccentric portions or crank pins 7 extending at opposite sides of the axis of the axles 4.

Each crank pin 7 passes through one of two vertically slotted pieces 8 which may have vertically extending walls including a narrow space. The top of each piece 8 forms an elongated, horizontally extending bar 9 of preferably rectangular and hollow shape. This bar fits a guide member 11 slidably whereby the piece 8 forms a slide member or sled. The two guide members 11 are positioned under and permanently affixed to the platform 2 and are open 20 at the bottom to allow movement of the downward extending portions of the sleds 8. An additional guidance for the sled may be provided by bolts 12 passing through bores of the bars 9 horizontally and reaching through slots 13 in the sides of the guide members 11. The slots 13 have a length sufficient to allow movement of the sleds with the bolts 12 to and fro as far as corresponds to the eccentricity of the crank pins 7.

A pin or post 14 is affixed to and extends vertically upward from each sled 8 and reaches through a slot 15 which extends through the upper side of the guide member 11 and through the platform 2. Also the slots 15 have a length sufficient to allow movement of the sled 8 as far as this sled is driven by the crank pins 7. The top of each pin 14 carries a plate 16 from the front and 35 rear end of which abutments 17 rise. Preferably the piece 16—17 is made of transparent plastic material in order to make this piece less conspicuous.

A pole 18 is affixed to and rises vertically from the center of the rear end of the platform 2. This pole holds 40 a doll 19 preferably in the following manner: A belt 21 passes through a slot 22 crossing the pole 18 and is fastened about the waist of the doll 19 so that the pole is concealed behind the doll and the belt appears as a part of the doll's clothing.

The feet 23 of the doll form the lower ends of legs 24 which are movably connected to the doll's trunk in any well known manner whereby the feet can move to and fro. Each foot 23 reaches into the space of a pair of abutments 17 affixed to the same plate 16.

The platform 2, walls 3, guides 11 and pole 18 form 50 together a frame which is supported on the wheels 5 and which is provided with driving means, preferably, in the following manner: A tubular or channeled member 25 is affixed to the lower side of the platform 2 near the rear end thereof and has an opening facing toward the rear side of the toy. An identical member 25 is affixed under the front end of the platform and has an opening 55 toward the front side of the toy. A handle has an end portion 26 snugly fitting the opening or channel of either member 25. Another, elongated portion 27 of the handle extends from the end 26 in angular direction upward away from the frame. A leg 28 is affixed to the handle where the portions 26 and 27 meet and reaches down almost as far as the wheels 5 whereby, when the handle is not held, the toy will tilt a little to the side of the handles 60 and will rest stably on the leg 28 and the wheels 5. The parts 26, 27 and 28 may be made of tubes which are connected, for example, by welding. The handle portion 27 preferably comprises a plurality of telescopically engaging parts. For example, an upper end portion 29 enters a 65 lower portion of the handle slidably whereby the length of the handle can be adjusted according to the size of the

child using the toy. The adjusted length of the handle can be fixed in any known and suitable manner, for example, by means of a screw 31.

The drawing shows the handle attached to the rear of the frame so that the toy can be pushed in the forward walking direction of the doll. If it is desired to pull the toy in this direction, the handle is disengaged from the shown position and is secured to the front of the frame by inserting the handle end 26 into the front member 25. This transfers simultaneously the leg 28 from the rear side to the front so that the toy can stand also in the latter position of the handle.

When the toy is pushed or pulled, the wheels 5 roll along the ground and turn the crank shaft 6 whereby the sleds 8 engaged by the crank pins 7 are caused to oscillate in the walking direction. The abutments 17 oscillating with the sleds 8 move the feet 23 to and fro in a manner simulating walking movements of the doll.

The doll 19 may be replaced by another doll. Any doll used in the described toy may be made and clothed in well known manner like any ordinary doll. The sizes of the exchangeable dolls may vary in certain limits, and the height and length of the belt 21 can be easily adapted to these different sizes. An adaptation of the steps made by the feet results from the fact that feet of smaller dolls will not fill the space between the abutments 17 completely, but will reach between the abutments with some clearance whereby the abutments will transfer only a part of their oscillating movement to the feet.

I desire it understood that my invention is not confined to the particular embodiment shown and described, the same being merely illustrative, and that my invention may be carried out in other ways within the scope of the appended claims without departing from the spirit of my invention as it is obvious that the particular embodiment shown and described is only one of the many that may be employed to attain the objects of my invention.

Having described the nature of my invention, what I claim and desire to protect by Letters Patent is:

1. Apparatus for moving the legs of a doll to simu-

late a walking motion of the doll, including, a frame, at least a pair of guide members on the frame, each guide member extending along the frame in a direction having a substantial longitudinal component, at least a pair of bars each slidable within a different one of the guide members, at least a pair of sleds each extending from a different one of the bars in a direction having a substantial vertical component for movement with the bars, each of the sleds being slotted in a direction having a substantial vertical component, an eccentric crank disposed within the slots in the sleds and rotatable with the wheels for converting the rotary movements of the wheels into reciprocating movements of the sleds and bars in the guide members, the frame being slotted above the bars in a direction corresponding to the reciprocating movements of the bars, at least a pair of plates each being coupled to a different one of the bars through a different one of the slots in the frame for transferring the reciprocating movement of the bars to the legs of the doll, a channeled member attached to the frame, a handle supported by the channeled member and extending upwardly from the frame for facilitating movement of the apparatus, and a leg extending downwardly from the handle for producing a stabilized resting of the apparatus.

2. Apparatus as set forth in claim 1, in which a support member extends upwardly from the frame and receives a belt for strapping the doll in fixed position with the feet of the doll disposed on the plates for reciprocating motion.
